UNITED STATES PATENT OFFICE.

SAMUEL W. TRAYLOR, OF ALLENTEWON, PENNSYLVANIA.

TURRET-SHOOTING BATTERY.

Application filed March 26, 1924. Serial No. 701,946.

To all whom it may concern:

Be it known that I, SAMUEL W. TRAYLOR, a citizen of the United States, and a resident of Allentown, in the county of Lehigh and 5 State of Pennsylvania, have invented an Improvement in Turret-Shooting Batteries, of which the following is a specification.

My invention relates to a turret shooting battery which comprises a device which is 10 adapted to float in the water and which also is adapted to carry a person in concealment so that ducks may approach within shooting distance without becoming disturbed and frightened.

15 The general object of the invention is to provide a battery of the character and for the purpose indicated having means whereby a person who occupies the battery which is floating in the water may with facility 20 and readiness shift his position as may be desired so as to place himself in proper shooting relation to the direction from which the ducks may be approaching the battery: that is, the place of concealment.

25 It is also an object of the invention to provide a battery of the character indicated with means whereby the concealment of the person occupying the same may be more effectually accomplished than by the employment 30 of any device of similar character of which I am aware.

Another object of the invention is to provide the battery with novel means whereby in case of emergency, such as a sudden 35 storm, the plane of the top edge thereof may be elevated temporarily for the purpose of preventing water from washing over the top of the battery and thereby causing the possible sinking or submersion of the same.

40 Other objects and advantages of the invention will be pointed out in the detailed description thereof which follows or will be apparent from such description.

In order that the invention may be readily 45 understood and its practical advantages fully appreciated, reference may be had to the accompanying drawings in which I have illustrated one form of mechanical embodiment thereof. However, it will be understood, that the invention is susceptible of embodiment in other forms of construction than that shown and that changes in the details of construction may be made within 50 the scope of the claims without departing from the said invention. 55

In the drawings:

Fig. 1 is a top plan view of a turret shooting battery embodying the invention, a portion of which is shown as being covered with canvas or similar material while the remaining portion thereof is shown with such canvas or other material removed; 60

Fig. 2 is a vertical sectional view taken on the line 2—2 of Fig. 1;

Fig. 3 is a vertical sectional view taken 65 on the line 3—3 of Fig. 1;

Fig. 4 is a transverse sectional view taken on the line 4—4 of Fig. 2; and

Fig. 5 is a perspective view of a removable attachment for the battery adapted to 70 effect more complete concealment of a person who may occupy the battery.

Referring to the drawings: 1 designates a tank the lower end of which, which is adapted to be submerged within water, is 75 hermetically sealed or closed by a bottom *a*. The tank 1 is provided near its upper edge with an angle plate member 2 of annular or circular form, the vertical flange 3 of which is secured by means of rivets 4 to the outside 80 of the wall of the said tank. Deck portions or boards 5, the inner edges of which are of circular shape as indicated at 6 so that they may fit closely against the outer side of the vertical wall of the tank 1, are secured by 85 means of bolts 7 to the horizontal flange 8 of the said angle plate. It will be observed that there are four of these boards and that the ends of the said boards abut along lines radial to the tank 1 as indicated at 10. 90 Preferably the adjoining or abutting ends of the boards 5 are reinforced by means of overlapping plates 11 which are secured to the adjacent portions of abutting boards. The outer portion of the frame structure is 95 connected with the outer edges of the boards 5 previously referred to. The said frame structure comprises a rigid portion which includes the flange-like boards 15, 16, 17 and 18 which are secured in any suitable manner to the outer edges of the boards 5. The opposite ends of the flange-like boards 15 and 17 extend transversely of and beyond the boards 16 and 18 and may if desired be secured to the opposite ends of the latter. 100 Boards 19 and 20 are secured to the oppo-

105

site ends of the boards 15 and 17 and as indicated in Figs. 1 and 2 extend a considerable distance beyond the said boards 15 and 17. Boards 21 and 22 are secured to the 5 lower edges of the boards 16 and 19 and 18 and 20 and co-operate therewith to form boxes which are adapted to be closed by hinged lids 23 and 24. These boxes may be employed for holding weights which may 10 be employed to control the depth of submersion of the tank 1 within the water. The weight required to be placed in the said boxes will depend upon the weight of the person occupying the battery. The said 15 boxes may be employed also for storing articles of various kinds the storage of which may be desirable. The weights in the said boxes are indicated at 25.

The outer ends of the boards 19 and 20 20 are connected together by means of bars 27 and 27^a. A bar or strip 28 also extends between the said boards 19 and 20 and connects the same. Strips 30 arranged in spaced relation to each other are secured at 25 their opposite ends to the board 15 and bar 27. Like strips 31 are secured at their opposite ends to the board 17 and bar 27^a. Swinging frame members 35, 36, 37 and 38 are hingedly secured to the bars 27, 19, 27^a 30 and 20 by means of hinges 40. It will be observed that between the opposite ends of the frame member 35 and the adjacent ends of the frame members 36 and 38, and also between the opposite ends of the frame member 37 and the adjacent ends of the said frame members 36 and 38 corners are formed within which triangular-shaped frame members 41, 42, 43 and 44 are hingedly supported. The said hinges are indicated at 35 45 and by means thereof the said triangular-shaped frame members are connected with the opposite ends of the frame members 36 and 38. A frame member 50 is also hingedly connected by means of hinges 51 40 to the outer edge of the frame member 37. It will be observed that there is no corresponding frame member at the opposite end of the structure.

For the purpose of more effectually 50 sealing the structure from ducks or other fowl which may approach the neighborhood of the battery both the rigid and oscillatable or flexible portions of the structure are covered by means of flexible material, such as canvas, indicated at 60. The canvas is slit along lines as indicated at 61 55 between the triangular frame members 41, 42, etc., and the adjacent opposing ends of the frame members 35 and 37. The canvas 60 should be painted so as to resemble as nearly as may be practical or possible the appearance of the surrounding water upon the surface of which the said flexible portion of the frame structure rests. The said flexible 65 portion of the structure moves or oscillates

in harmony with the waves or in harmony with the vertical movements or pulsations of the water within which the battery may be floating. By this means the likelihood of the battery or device being visible to approaching birds, such as ducks, geese, etc., is greatly reduced.

As an important feature of my invention I have provided within the tank 1 a relatively shallow tub or pan-like member 65 75 having a bottom 66 which is pivotally held in place by means of a king bolt or pin 67 which is connected with and projects upwardly from the bottom *a* of the tank 1. The member 65 is rotatable upon the king bolt or pin 67 and to facilitate such rotation I have provided ball bearings at 70 upon which the bottom 66 of the member 65 is supported. In order to prevent tilting of the said member 65 and also to facilitate 80 the rotation of the same about the king bolt or pin 67 I have provided balls 71 which are interposed between the bottom 66 of the member 65 and the bottom *a* of the tank 1. The said balls 71 are situated in spaced relation to the center of the bottom 66 as shown. I have provided a seat 72 within the member 65 which is provided with rollers 73 mounted on tracks or guides 74 upon the bottom 66 of the said member 65. It will be apparent that the seat 72 may be moved inwardly or outwardly so as to vary its position to suit the desires or requirements of the occupant of the battery. The 90 position and attitude of an occupant of the battery is indicated in Fig. 2 of the drawings.

For the purpose of more effectually concealing the occupant of the battery from approaching ducks, geese or the like I have provided the segmentally-shaped frame structures 76 each of which is provided with three legs 77 as shown which are adapted to project downwardly into the tub or pan-like member 65 and to extend through staples 80 secured upon the inner side of the side walls of the said member. The legs 77 are provided with notches 81 at their lower ends which fit over the flange 82 of the bottom 66 of the member 65. The legs 77 support the frames 76 in planes substantially coincident with the plane of the top edge of the tank 1. The frames 76 are covered over with canvas as indicated at 83. The inner straight edges of the frames 76, when the latter are in position as shown in Figs. 1 to 3 of the drawings, are parallel with and are spaced from each other. The distance of separation between the parallel straight edges of these frames is sufficient to permit the occupant to straighten up and stand erect in the battery should he desire to do so.

As has already been described the tub or pan-like member 65 is mounted to rotate

within the tank 1. This is of very great advantage when the occupant is desirous of changing from a position in which he may be facing to another in which it may be more 5 convenient for him to shoot at ducks, geese, or the like which may be in shooting distance of the battery. The occupant of the battery may readily rotate the member 65 by placing an arm or hand against the relatively stationary wall of the tank 1 and pushing upon the same. Such action will cause rotative movement of the said member 65 so as to place the occupant in whatever position he may wish to take.

10 It will also be observed that, as already indicated, there is no frame member at the left hand end of the battery, having reference to Fig. 1 of the drawings, corresponding to the frame member 50. The latter, 20 therefore, acts somewhat in the capacity of a rudder so as to cause the battery to assume a position with the left hand end thereof, having reference to Fig. 1 of the drawings, facing in the direction from which the wind 25 may be blowing or in the direction from which the water within which the battery is floating may be flowing.

It may happen that by reason of the sudden springing up of the wind waves of considerable height may be generated in a body 30 of water within which the battery may be floating so that it might happen that unless preventive means were employed the water would wash over the wings of the battery 35 and over the top edge of the tank 1 and fill the latter thereby causing the battery to sink. In order to prevent such an occurrence I have provided a safety device comprising a circular strip of flexible material 40 90 one edge of which is secured to the inner side of the upper edge of the tank 1 by means of a band 91. The edge of the circular strip 90 is secured between the said band and the adjacent portion of the upper edge of the 45 tank 1. The outer or rather the movable edge portion of the circular strip 90 is provided with a steel ring or hoop 92 of a diameter such that it may be moved down into the tank 1 as shown in full lines in 50 Figs. 1, 2 and 3 of the drawings. This is the position normally occupied by the said strip but in case high winds should rise or develop which might induce waves in the 55 water of a height to cause them to wash over the top edges of the tank 1 the occupant of the battery may stand therein and elevate and hold the ring or hook 92 together with the circular band 90 in a position above the 60 top edge of the tank 1 as indicated in dotted lines at 93 in Fig. 2.

It will be apparent to those skilled in the art that by reason of the fact that the canvas or other covering, which is secured over the rigid and hingedly connected frame 65 structure as previously described, is painted

a color such as to give it the appearance of the surrounding water, and by reason of the further fact that the hingedly connected and flexible portions of the said frame structure ride up and down upon the waves of the 70 water in which the battery may be floating the visibility of the battery is decreased to such an extent that approaching birds, such as ducks, geese, and the like, are not likely to observe the same.

75 It will also be apparent that by reason of the fact that the occupant of the battery is supported upon the rotatable member 65 he may readily and quickly change from one position to any other which he may desire.

80 The practical advantages incident to my invention will be apparent to those who are familiar with devices of the character shown.

Having thus described my invention, what I claim and desire to secure by Letters Patent is:

85 1. In a turret shooting battery, the combination of a tank adapted to float in water, with means mounted within the said tank and rotatable about a substantially vertical 90 axis, said means being adapted to support a person occupying the said battery.

95 2. In a turret shooting battery, the combination of a tank adapted to float in water, a member mounted in the said tank upon the bottom thereof, which member is adapted to rotate about a substantially vertical axis, and a seat mounted upon the said rotatable member.

100 3. In a turret shooting battery, the combination of a tank adapted to float in water, a pan-like member located within said tank, roller bearings interposed between the bottom of said pan-like member and the bottom of said tank and supporting the former, and a slidale seat mounted within and upon the bottom of the said pan-like member.

105 110 4. In a turret shooting battery, the combination of a tank which is adapted to float in water, a rotatable supporting member mounted within and upon the bottom of the said tank, and concealing means supported upon said rotatable member for more effectually concealing a person located upon the said rotatable member within the said tank.

115 120 5. In a turret shooting battery, the combination of a tank which is adapted to float in water, a rotatable pan-like member mounted within and upon the bottom of said tank, the side walls of said pan-like member being provided with two groups of staples which groups are arranged in opposed relation to each other, segmentally shaped frame members each of which is provided with a plurality of depending legs which are adapted to engage the said staples, the straight edges of said segmentally shaped frame members occupying inner positions in 125 130

spaced opposed relation to each other when supported upon the said rotatable member, and coverings for the said segmentally shaped frame members, substantially as described.

6. In a turret shooting battery, the combination of a tank which is adapted to float in water, which tank is provided with a rotatable supporting means adapted to support a person therein, a frame structure extending laterally from the periphery of the said tank adjacent the upper edge thereof, said frame structure comprising rigid and flexible portions, one or more receptacles embodied within the rigid portion of the said frame structure, and a flexible covering for the said frame structure.

7. In a turret shooting battery, the combination of a tank which is adapted to float in water, movable means within the said tank for supporting an occupant thereof, a frame structure extending laterally from the periphery of the said tank adjacent its upper edge, said frame structure comprising a rectangular rigid portion and rectangular frame portions having flexible connection with the respective edges of the said rigid portion, and triangularly shaped flexibly connected portions situated in the corners between adjacent portions of the said rectangular flexibly connected frame portions, and a flexible covering for the said frame structure.

8. A turret shooting battery comprising a tank which is adapted to float in water, which tank is provided with a frame structure extending laterally from its periphery at a point adjacent the upper edge thereof,

which frame structure comprises an inner rigid portion of rectangular shape, rectangularly shaped frame members hingedly secured to the edges of the said rigid portion, triangularly shaped frame members situated in the corners between adjacent ends of the said rectangularly shaped frame members, the said triangularly shaped members respectively having hinged connection with one end of a frame member, a frame member having hinged connection with one edge of one of the said rectangularly shaped frame members, and a flexible covering for the said frame structure.

9. In a turret shooting battery, the combination of a tank which is adapted to float in water, which tank is provided with a rotatable supporting means adapted to support a person therein, a frame structure extending laterally from the periphery of the said tank adjacent the upper edge thereof, and a covering for the said frame structure.

10. In a turret shooting battery, the combination of a tank which is adapted to float in water, which tank is provided with a rotatable supporting means adapted to support a person therein, a frame structure extending laterally from the periphery of the said tank adjacent the upper edge thereof, said frame structure comprising rigid and flexible portions, and a flexible covering for the said frame structure.

In testimony that I claim the foregoing as my invention, I have hereunto signed my name this 24 day of March, 1924.

SAMUEL W. TRAYLOR.
